UNITED STATES PATENT OFFICE.

CHARLES H. HORTON, OF PAINESVILLE, OHIO, ASSIGNOR TO THE HORTON MANUFACTURING COMPANY, OF SAME PLACE.

BRICK-PRESS.

SPECIFICATION forming part of Letters Patent No. 660,110, dated October 23, 1900:

Application filed December 28, 1898. Serial No. 700,504. (No model.)

To all whom it may concern

Be it known that I, CHARLES H. HORTON, a resident of Painesville, Lake county, and State of Ohio, have invented certain new and useful Improvements in Brick-Presses; and I do hereby declare the following to be a full, clear, and exact description of the invention, such as will enable others skilled in the art to which it pertains to make and use the same.

10 My invention relates to brick-machines, and more especially to such machines as form bricks, slabs, or the like by compressing the same into a mold or series of molds of suitable or predetermined configuration.

15 My invention consists in certain features of construction whereby the pressing-plunger is contained and operated within the "mud" or clay chamber.

20 My invention also consists in the peculiar construction of the mold-feeding device, whereby the molds are fed in rotation at proper intervals under the plunger or compressor and whereby the mold-feeding device is so constructed that any overstrain brought 25 to bear upon the feeder-head in feeding the molds is compensated for or taken up by a union or joint between the driving mechanism which operates the feeder-head and the said head.

30 My invention also consists in the peculiar construction of the mold-feeding apparatus as a whole and in the movement-conveying gearing for said mold-feeding device.

35 My invention further consists in an adjustable driving mechanism connected with the plunger of the press, whereby the amount of mud or clay fed to the die and mold is predetermined according to the desired density of the brick or slab or according to the quality 40 of the mud or clay employed.

My invention also embodies other details of construction, which will be hereinafter fully set forth and claimed.

45 In the drawings, Figure I is a view in longitudinal vertical section of a brick-machine of the class above set forth which embodies my invention. Fig. II is a view in front elevation of my machine. Fig. III is a sectional view illustrating the attachment of the plunger-rods to the press-plunger. Fig. IV is a 50 sectional plan view of my machine, taken on

line IV IV, Fig. I. Fig. V is a perspective view of the die and mold used in connection with my machine.

A represents the pugging-chamber. The 55 pugging-chamber A is cylindrical except at its front end, which is rectangular in cross-section. A mold-filling plunger M is operatively supported in the front end of the pugging-chamber, and under the mold-filling 60 plunger is located a die, as hereinafter more fully described. A portion of the bottom of the pugging-chamber at its front end is depressed below the level of the rest of the bottom, forming a pocket a for receiving deposits 65 of stones or other heavy substances contained in the mud and preventing the same from being carried onto the face of the die. In the drawings I have shown this pocket a formed by inclining the bottom of the pug- 70 ging-chamber toward the front end and extending a gate S transversely of the pugging-chamber immediately behind the die. I prefer this construction, as the gate S thus forms one side of the press-box a², surround- 75 ing the die, the other sides of the press-box a² being respectively the lower portion of the front wall of the pugging-chamber and the portions of the two sides of the pugging-chamber between the said front wall and the 80 gate S.

In order that the mold may be well packed, the press-box a² is designed to hold more mud under the plunger than is necessary to fill a mold, and in order to allow the escape of the 85 excess of mud from under the plunger the gate S, which forms the rear end of the press-box, is hinged and held in position by means of a spring, which allows the gate to yield and permits the surplus mud to escape back 90 into the pugging-chamber when the mold has been filled. The construction of this gate is more fully described hereinafter.

The receptacle A is provided at its ends A' A² with journals, which act as bearings for 95 a shaft B. The shaft B is provided with suitable tempering blades or knives C, properly secured thereto and revolving therewith. These tempering-blades C may be of any suitable construction and are secured to a shaft B, 100 either, as illustrated in the drawings, by means of divided couplings c or in any other

suitable manner, so as to be properly disposed around said shaft and be at proper distances apart. The function of the tempering blades or knives C is to properly cut up 5 or temper the clay or mud, bringing it to a proper state of consistency.

D represents wipers, which are constructed of proper width and angle to advance the clay to the press when the plunger of the 10 same is elevated.

E represents the die, which is shown more clearly in Fig. V of the drawings. The die E, I prefer to form with one of its sides (the front side) open and with suitably-spaced inverted-V-shaped bars e. The spacing of the 15 bars e is predetermined by the width of the brick or slab to be pressed, and hence is predetermined by the divisions in the mold to be used. It will be noticed that the bases of the 20 bars e are somewhat greater than the width or thickness of the divisions of the mold, as illustrated in Fig. V. The object in thus constructing the die E is to properly divide the mud or clay and direct the same into the 25 several chambers or compartments of the mold. The object in overlapping the partitions of the molds by means of the bases of the bars e is to prevent the mud or clay as it is being pressed into the molds from "striping" 30 the sand or lubricant from the sides of the molds. By forming the die with an open side, as illustrated in Fig. V, stones or foreign substances are more readily pushed or forced out from said die.

F represents a mold, which may be of any 35 suitable construction, material, or contour, adapted to properly receive and give configuration to the material received and compressed therein. The molds F are preferably 40 subdivided by means of partitions f; but this is not essential, inasmuch as slabs may be formed by my machine which will require the full mold to receive and shape them. In regard to the depth of the mold this is predetermined 45 according to the thickness of the bricks or slabs to be formed.

G represents the mold-feeder head, which I prefer to construct as illustrated in the drawings (see Fig. I) and provide it with 50 wheels or rollers g, which have traction upon or are guided by suitable tracks or grooves, which may be formed either integral with or be connected to a vertically-adjustable bed H. The mold-feeder head G is reciprocated back 55 and forth a suitable distance along the bed H, so as to allow of sufficient space for receiving and advancing the molds F, which are fed at the side of the machine in advance of the mold-feeder head.

60 In order to properly operate or reciprocate the head G at proper intervals and give the same the proper throw according to the width of the mold, I have provided a construction which is as follows:

65 G' represents a two-part pitman jointed at g'. The longer arm G² of the pitman G' is pivotally connected, as at g², with the head

G, and the shorter arm G³ of said pitman G' is suitably-connected to an adjustable wrist-pin i. The adjustable wrist-pin i is secured 70 to a beveled pinion I, which is properly journaled to the casing A and rotates horizontally. The beveled pinion I is so constructed and mounted as to mesh with a segmental beveled gear K', which is secured to and revolves with 75 the driving-gearing K, attached to the pugging-shaft B. The segmental bevel-gearing K' is provided with a sufficient number of teeth to give to the bevel-pinion I one revolution, thus transmitting to the pitman G' a single throw 80 in both directions. During a portion of the revolution of the gear K the bevel-pinion I is at rest, which stops the movement of the pitman G' and its feeder-head G and allows time for the introduction or feeding of the molds 85 to the machine.

Inasmuch as it is essential that the teeth of the pinion I and the segmental bevel-gear K' properly mesh or engage as the said segmental gear returns to position, so as to engage the teeth of said pinion, I provide the pinion I with an open space i², (see Fig. IV,) and I provide the said beveled pinion with a lug or projection i³, located so as to be in position to be engaged by a co-operating 95 lug k, located at the starting end of the said segmental bevel-gearing K'. (See Fig. I.) The object in providing the lugs i³ and k is to obtain an absolute and positive start and mesh between the segmental gearing K' and the bevel-pinion I.

The object in forming the pitman G' in two parts, as G² G³, and pivoting those parts together, as at g', is to allow the said pitman to buckle when under undue strain, and my preferred construction for accomplishing this object is illustrated in Fig. IV in solid and dotted lines. The solid lines illustrate the normal position of the pitman, and the dotted lines illustrate the pitman in position which it assumes when under undue strain. As illustrated in Figs. I and IV, the parts of the pitman G² and G³ are pivotally connected by a pintle g' and are so connected that when the pitman is in its normal position the axial lines 110 of the parts G² and G³ are at a slight angle to each other, or, in other words, the direct thrust is brought to bear to a certain extent beyond the axial line of the pitman. In order to keep the pitman in its normal position, 115 it is essential that some power or force be applied in order to retain the parts G² and G³ from buckling under normal strain, and for this purpose I prefer to employ a spring L, such as is illustrated in Fig. I. Spring L surrounds the pintle g' and has its two arms l and l' respectively engaging lugs g³ g⁴ near the pivotal portions of the parts G² and G³ of the pitman. The tension of the spring L is such as to sustain the pressure along the pitman under normal condition and to allow the 120 said pitman to buckle under undue strain. While I have in this connection shown and described a spring for accomplishing this pur-

pose and have also set forth and illustrated my preferred construction of spring and method of connecting the same, it is apparent to those skilled in this art that other constructions of springs and other methods of connecting the same may be employed.

The platen or table H is mounted in the machine beneath the plunger of the press and is provided with gratings h and rollers h', as usual, and is adjusted in a vertical direction by means of jack-screws H', properly mounted in the framework of the machine and adapted at their upper end to support the platen H. Inasmuch as the wear on the platen at the part H², where the molds are projected after being charged, is great and inasmuch as this wear if allowed to progress to any great extent would be detrimental to the proper working of the machine, I have provided a removable plate H², which is preferably constructed of gridiron form or open-work of bars and cross-bars. Plate H² is detachably secured in position on the table or platen H in any suitable manner—such, for instance, as shown in sectional view, Fig. I, by means of a bolt and nut h³, which engages the clamping-bar h³, which in turn engages a cross-bar h⁴ and holds the detachable portion or plate H² in position. The plate H² may be made in one or more parts, and, as I have illustrated in Fig. IV of the drawings, I prefer to construct it of two parts, and in this case two fastening devices, such as h² h², would have to be employed. By making the plate H² separate from or detachable from the platen or table H, I am enabled to remove or replace it without the necessity of reconstructing, refinish, or replacing the platen as a whole, and this is a material feature of my machine.

The method of operating the press-plunger M of my machine is as follows: The plunger M is located so as to operate in the forward end of the casing A. A walking-beam N is pivoted at one end, as at n, to a standard N', which in turn is secured to the pugging-case A in any suitable manner. The walking-beam N at its outer end is connected to the upper end of a pitman O by means of a ball-and-socket joint N², which allows of a universal movement between the said pitman O and walking-beam N at this connection, which is essential on account of the varied movements of the same during the operation of the machine. At the lower end of the pitman O an opening O' is provided, or, more truly speaking, the said pitman may be made in two parts, as illustrated in front elevation, Fig. II. At both sides of the opening O', I provide recesses o, registering with each other and adapted to receive and retain a lifting-plate P, which is received and retained in one of the series of recesses o. The object in providing the recesses o and in adjusting the plate P by means of the same is to vary the throw of the plunger M in its upward or backward movement, and thus graduate the amount of clay to be fed or compressed by

said plunger. It will be understood that this is essential according to the quality or quantity of mud or clay used and according to the required density of the brick, slab, or other product of the machine.

M' M' represent plunger-stems which are connected to the plunger M in any suitable manner, so as to raise and lower the same the predetermined distance. The stems M' M' receive their motion through the walking-beam N and are connected thereto by a "block" M², preferably adjustably secured to said walking-beam. Said block in turn is pivotally connected, as at m, to said stems M'. The extent of the motion of the stems M' M' and connected plunger M is determined positively in its downward direction by the downward throw of crank R, with its attached wrist-pin R', and upwardly by the throw of the wrist-pin R', in connection with the adjustable plate P and its receiving-slots o.

It will be noticed that the plunger M is contained and operates within the mud or clay chamber A³, which contains the mud or clay at proper consistency to form the product, and, as it were, the plunger M in its downward movement slices off from the mass contained within said chamber and feeds through the die E and properly compresses into the mold the predetermined amount of material to form the product. The advantage of this construction or location of the plunger M is that clay of a proper consistency is always at hand to be compressed through the dies and into the mold and that a constant supply of the mud or clay is always at hand for this purpose.

The gate or safety-valve S is mounted upon suitable bearings at its ends, and, as illustrated in Fig. II of the drawings, one of the bearings is provided with an arm S', securely attached thereto, and provided at its outer or free end with a spring S³ or the equivalent of the same, which may be a weight. The spring or weight acts upon the arm S' and is adjustable or changeable, so as to permit the proper tension being given to the gate or valve S. Inasmuch as various devices may be employed for regulating the tension of the relief valve or gate S, I have illustrated but one, which will be clearly understood from the drawings.

What I claim is—

1. In a brick-machine, the combination with a pug-mill, of a mud-press located wholly inside of the chamber of the pug-mill and adapted to press mud therefrom into a mold.
2. In a brick-machine, the combination with a horizontal pugging-chamber having an outlet at its bottom at one end, of a plunger located inside of said pugging-chamber, said plunger constructed and arranged to operate in the mud in the pugging-chamber and force it out through said outlet into a mold.
3. In a brick-machine, the combination with the chamber of a pug-mill having an outlet-opening, of a plunger located within the

chamber of the pug-mill and adapted to operate in the mud therein and force it, through said outlet, into a mold, and a yielding device located at the inner edge of said outlet and projecting into said chamber, substantially as and for the purpose set forth.

4. In a brick-machine, the combination with a pugging-chamber having an outlet in its bottom at its front end, of a plunger located in the pugging-chamber and adapted to operate in the mud therein and force it, through said outlet, into a mold, a part of the front end of the pugging-chamber forming one side of a press-box for said plunger, and a yielding device located at the inner edge of the outlet and projecting up into the said chamber so as to form the opposite side of the press-box.

5. In a brick-machine, the combination of a pugging-chamber having an outlet in its bottom at or near one end, a die in said outlet, a mold-support under the die, a vertically-movable plunger disposed within the pugging-chamber over said outlet and adapted to operate in the mud in said chamber and means for operating said plunger.

6. In a brick-machine of the character indicated, a pugging-chamber, a pugging-mill operating in said chamber, a vertical mold-filling plunger operating in the front end of said chamber, a die located beneath said plunger, and a pocket formed in the bottom of the pugging-chamber behind the said die and adapted to receive and retain deposits of heavy substances contained in the mud, preventing the same from being carried onto the surface of the die, substantially as described, for the purpose set forth.

7. In a brick-machine of the character indicated, a pugging-chamber having a portion of its bottom, near its front end, inclined to the front and below the general level of the said bottom, a mold-filling plunger operating in the front end of said chamber, a die located in the bottom of said chamber beneath the said mold-filling plunger, a division-gate extending transversely of the said pugging-chamber in the interior thereof and immediately behind the said die, and means for holding said gate in a vertical position, substantially as described and for the purpose set forth.

8. In a brick-machine of the character indicated, a pugging-chamber, a pugging-mill operating in said chamber, a vertical mold-filling plunger operatively supported in the front end of said chamber, a die located beneath said plunger, a press-box surrounding said die, the rear end of said press-box being yieldingly supported in its vertical position, and adapted to open toward the interior of the pugging-chamber so as to allow the surplus mud, under the plunger, to escape back into the pugging-chamber, substantially as and for the purpose set forth.

9. The combination with a pugging-chamber, a pugging-shaft having bearings in said

chamber, and means for operating said pugging-shaft, of a mold-filling plunger operating in said pugging-chamber, and means for operating said mold-filling plunger, comprising a crank-arm keyed to the said pugging-shaft, a vertical adjustable pitman having its lower end operatively connected with the said crank-arm and provided, at its other end, with a socket, a lever pivoted at one end to a rigid support and provided with a ball at its other end adapted to fit into the said socket in the end of the said pitman, and pivotal connection between the said lever and the shaft of the said mold-filling plunger, substantially as described, for the purpose set forth.

10. In a brick-machine of the type set forth, the combination with a pugging-shaft, of a gear-wheel for operating the said shaft, said gear-wheel being provided, on one of its faces, with a segmental bevel-gear, which intermittently engages a bevel-pinion, a wrist-pin connected to said bevel-pinion, an adjustable pitman connected to said wrist-pin, and a mold-filling device operated by said pitman, substantially as and for the purpose set forth.

11. In a brick-machine of the type set forth, the combination with a plugging-shaft, of a crank located at its forward end, a pitman connected to said crank, said pitman, in turn, adjusted so as to have a positive predetermined downward throw when operated by said crank, and being provided with means whereby the upward movement of the pitman may be varied or adjusted, a rocking beam having ball-and-socket connection with said pitman, and a plunger pivotally connected to said rocking beam, substantially as described, for the purpose set forth.

12. A brick-machine of the type set forth, comprising a platen or table; a mold-feeder head reciprocating thereon so as to feed the molds to proper position; a pitman connected to said mold-feeder head, said pitman being formed in two parts and pivoted together; the pivotal connection between the parts being such as to feed the molds under normal conditions and to buckle or compensate under abnormal strain, substantially as and for the purpose set forth.

13. In a brick-machine of the type set forth, a mold-feeding device comprising a feeding-head, a pitman pivotally attached thereto, said pitman being formed in two parts, said parts being out of alinement and pivotally connected, and means, substantially such as set forth, for retaining said pitman in normal position under normal strain and permitting said pitman to buckle or compensate under abnormal strain, substantially as and for the purpose set forth.

14. In a brick-machine of the type set forth, a mold-feeding device comprising a feeder-head, a pitman connected to said head, said pitman being operatively connected and adjustably connected with a crank bevel-gear, in combination with a segmental bevel-gear

for intermittently operating the mold-feeder through said crank bevel-gear, substantially as and for the purpose set forth.

15. In a brick-machine of the type set forth, 5 a plunger-operating device consisting essentially of a rocking beam pivotally connected at one end, and an adjustable pitman connection located at the opposite end, and a crank for operating said pitman and through 10 it the rocking beam, the connection between the pitman and the rocking beam being a ball-and-socket connection, substantially as and for the purpose set forth.

16. In a brick-machine of the type set forth, 15 a mold-feeding device comprising a suitable head for contacting with and feeding said molds; a pitman connection connected to said head, and means or mechanism intermittently operated for intermittently operating 20 said mold-feeder head, said means comprising a bevel-pinion provided with a wrist-pin

for connecting and operating the pitman, and a driving bevel-gear of segmental form, substantially as and for the purpose set forth.

17. In a brick-machine of the type set forth, 25 mechanism for intermittently operating the mold-feeder, said mechanism comprising a segmental driving-gear; a pinion operated thereby; starters for properly meshing the segmental gear and the pinion, and a wrist- 30 pin connected to said pinion, in combination with a pitman connected to said wrist-pin, and a suitable feeder-head connected to and operated by said pitman, substantially as and for the purpose set forth.

Signed by me at Painesville, Ohio, this 25th day of November, 1898.

CHARLES H. HORTON.
